UNITED STATES PATENT OFFICE.

FRANK J. COURTNEY, OF SEATTLE, WASHINGTON.

CAN EMPTYING AND FLATTENING MACHINE.

1,376,798.

Specification of Letters Patent.

Patented May 3, 1921.

Application filed November 4, 1919. Serial No. 335,582

To all whom it may concern:

Be it known that I, FRANK J. COURTNEY, a citizen of the United States, residing at Seattle, in the county of King and State of Washington, have invented a certain new and useful Can Emptying and Flattening Machine, of which the following is a specification.

My invention relates to the art of can emptying and can flattening machinery, and more particularly to machinery designed to cut a rectangular metallic can on its end or ends so as to empty the said can and to fold said can into a flat form.

15 The can flattening and emptying devices as heretofore designed have not made efficient and suitable provision either for the smooth cutting of the edges of the can so as to avoid distorting said edges or for the prompt or 20 quick emptying of said cans after said edges are cut, said emptying not being subject to control so as to prevent objectionable splashing about of the liquid contents. Moreover if the edges of the end of a can are jammed 25 or distorted, such devices as heretofore designed have not been adapted to operate upon said cans.

The object of my invention is to provide a 30 device which will cut the end of a rectangular can on three sides in a smooth or clean cut manner, control the emptying of said can by subjecting the contents to a suction force while said contents are being removed from the can so that the contents are not splashed 35 about, and which will fold, flatten, trim, and count said cans. Furthermore, another primary object of my invention is to provide an improved cutter, having a continuous cutting edge and also an improved cutter having 40 a continuous cutting edge and trimming means designed to operate on cans whose edges are distorted or jammed.

The above general objects of my invention, together with others inherent in the same are 45 obtained by the mechanism illustrated in the following drawings, the same being merely a preferred exemplary form of embodiment of my invention throughout which drawings like reference numerals indicate like 50 parts:

Figure 1 is a view in side elevation of a device embodying my invention;

Fig. 2 is a view of one end in elevation of said device;

Fig. 3 is a view of the opposite end in elevation of said device;

Fig. 4 is a plan view on broken line 4, 4 of Fig. 1;

Fig. 5 is an enlarged cross-sectional view 60 on broken line 5, 5 of Fig. 1;

Fig. 6 is a view of a modified form of the upper portion of my device having trimmer knives disposed above the flattening rollers;

Fig. 7 is an enlarged longitudinal sectional 65 view of the box-cutter;

Fig. 8 is a top view of the box cutter;

Fig. 9 is an end view of a rectangular can with the three edges cut and ready to have said end folded inwardly:

Fig. 10 is a perspective view of a can with 70 the two ends cut and partly folded in toward one side;

Fig. 11 is a perspective view of a can with the ends folded back against one side as placed by the roller pushers;

Fig. 12 is a view of a can after being completely folded, and

Fig. 13 is a view of a modified form of a cutter embodying my invention.

Two members 14 and 15 form a guideway 80 in which each box-cutter 16 and 17, consisting of the knife 18 and the box part 19, may move back and forth, said members 14 and 15 having midway of their length an opening 20 and 21 in which are pivotally mounted 85 crushing members 22 and 23. (Figs. 1 and 5.) These members do not meet along their lower edges—so that an opening 24 is provided through which the liquid contents of the can to be emptied may escape, and they 90 also have perforations 25 for the same purpose. The members 14 and 15 are supported by the frame part 26 at each end of the machine. The said frame part 26 supports

under said box-cutters 16 and 17 a wheel 27 95 having cams 28 and 29 which serve to actuate rods 30 and 31 which have roller bearings 32 and 33. Having been forced forward by said cams, the rods 30 and 31 are retracted by springs 34 and 35. Levers 36 and 37 are 100 pivotally connected to said rods at 38 and 39 and to the frame portion by pivotal connections 40 and 41, 42 and 43 through arms 44 and 45. The levers 36 and 37 are similarly

pivotal connected to the rods 46 and 47 which are in turn pivotally connected to the box-cutters 16 and 17 so that said cutters may be caused to move forward and backward.

A chute 48 serves to conduct the full cans 96, which are to be operated upon, to the crushing members 22 and 23, and the tripper 49, Fig. 5 with its finger 50 disposed to engage a cam hereinafter described and its retracting spring 51 serves to feed the cans to the machine periodically one by one. A counting mechanism 52 with its trigger 53 serves to register the number of cans fed to the machine. A conveyer 54, Fig. 2 carries the cans 96 to chute 48. Flattening rollers 55, preferably armed with sharp gripping teeth at their ends, are positioned above the crushing members 22 and 23 and serve to complete the collapsing operation so that the walls of the can 96 are pressed tight against each other. The said rollers 55 also serve to remove the can 96 from the said crushing members. The deflector 56 directs the folded can 96 away from the machine.

On the outside of each of the crushing members 22 and 23 is formed a curved wing 57 and 58 against which is caused to bear periodically cams 59 and 60 respectively, said cams being mounted upon shafts 61 and 62, on the opposite extremity of which are fixed suitable gears 63 and 64 to actuate said cams whereby the crushing members may be moved forward after the ends of the can 96 are properly cut to partially flatten the can and push it upward so as to cause it to be gripped by the flattening rollers 55. Springs 65 and 66 retract the crushing members 22 and 23.

The box-cutters 16 and 17 (Figs. 6 and 7) are each provided with a three sided cutting edge, two of which sides are disposed at right angles to the other with a foremost point at 67 from which foremost point the cutting edge slopes evenly from said point to the edges 68 and 69 and then evenly on each side 70 and 71 so that a continuous cutting edge is provided from the said point to the lateral edges of the side oppositely disposed to said point. Roller 72 disposed at the end of rod 73 provided with a spring 74 is preferably caused to bear against that portion of the can nearest the uncut side 75. Where the cans to be flattened have but one end to be cut obviously, one cutter only would be necessary.

Suitable power connection is afforded through pulley 76 secured to shaft 77 on the opposite end of which is the bevel gear 78 intermeshing with bevel gear 79 on shaft 80. Upon said shaft 80 there is mounted the wheel 27 with its cams 28 and 29. Also, on shaft 77 is the sprocket wheel 81 over which a chain 82 passes to make connection with the small sprocket wheel 83, mounted on the

end of one of the flattening rollers 55. Furthermore, on shaft 77 is mounted the gear 84 which meshes with gear 85 mounted upon shaft 61 which in turn carries cam 59. Moreover, on shaft 61 is the gear 86 meshing with gear 87 which bears the sprocket wheel 88 over which a chain 89 passes to operate the conveyer 54.

In Fig. 6 is shown two rotary knives 90 and 91 mounted above the flattening rollers 55 disposed to trim the edges of the flattened can. These edges are usually irregular, having a large amount of solder adhering to them so that they must be removed before the tin of the can 96 can be reused. At the same time the said solder can be recovered and reused.

In the modified form of box-cutter Fig. 13, I provide on the side which is to leave one side of the can uncut, two short cutting points 92 and 93 the outside edges 94 and 95 of which points lie in the same plane as do the sides 70 and 71. These cutting points 92 and 93 serve to "true up" the can 96 and partially cut the fourth side on its margins.

The mode of operation of my device is as follows: The cams 28 and 29 are caused to bear against the bearings 32 and 33, thereby gradually forcing back the rods 30 and 31 so that the bottom part of the levers 36 and 37 is pushed outwardly, and the top part of said levers is forced inwardly, thereby actuating the box-cutters 16 and 17 in the operation of cutting against the ends of a can in the trough. The form of the cams 28 and 29, it will be observed, is such that they will cause the said box-cutters to move slowly while actually cutting the ends of the can, but while doing this the cams are working against the springs 34 and 35. By thus causing the force utilized in actuating the cutters to be opposed I produce a steady, even force which cooperates with my new form of cutter to produce a smooth clean cut edge at the end of the can. When the bearings 32 and 33 have reached the end of the curved surface of the cams, obviously the rods 30 and 31 will be urged by the springs 34 and 35 with great force toward the center of the wheel 27 and, then as the wheel 27 turns, the said cams will slowly force them outward again as a new can is to be operated upon. When the springs force the rods 30 and 31 inwardly they jerk the box-cutters 16 and 17 away from the end of the can and thereby create a suction on the liquid contents of the can which removes the contents with force and yet does not cause or allow the said contents to be unduly splashed about.

A small hole 97 in the end of the box-cutter is of sufficient size to allow the air within the box-like part of the cutter to escape as the cutter slowly enters the end of the can ("slowly" as compared to the backward movement of the

said cutter) but said hole is not so large as to prevent the creation of a suitable vacuum to induce the suction influence upon the rapid backward movement of the cutter. 5 The liquid contents are thus quickly and promptly removed upon the completion of the cutting of the ends of the can, and allowed to pass down through the opening 24 to suitable collecting pans not shown. Vents 10 25 assist in letting the oil escape from the guideway and crushing members. So soon as the three sides of the can are entirely cut, the spring operated rollers 72 push in the ends thereby assisting in emptying the liquid 15 contents into the box portion 19 of the cutter and so soon as this phase of the operation is well under way, the box cutter is withdrawn inducing the suction above described. The operation of the knives is 20 timed by the positioning of the cams 28 and 29 so as to cause one end to be cut just a little in advance of the other end so as to prevent the can ends meeting and being jammed against one another as they are 25 folded inwardly. Thereupon, the cams 59 and 60 press upwardly the crushing members 22 and 23 which partially flatten the can and coöperate with the suction force above described in emptying the can. Moreover, 30 these said crushing members, in crushing the can cause it to extend upwardly so that the can comes into engagement with the flattening rollers 55. These rollers complete the flattening of the can and also serve to 35 remove the can from the crushing members 22 and 23. When the edge trimming knives 90 and 91 are provided, Fig. 13, the said rollers 55 further serve to force the can through said knives whereby the irregular 40 edges are removed leaving a smooth edged plate of tin ready for baling. The speed of the rollers 55 is such that the flattened can is ejected with force striking deflector 56 so as to fall away from the machine on a 45 conveyor.

After the crushing members 22 and 23 have delivered the can to the flattening rollers 55, the springs 65 and 66 cause the said members to resume their inactive position 50 in the openings 20 and 21. As the cam 59 turns it engages the finger 50 of the tripper 49, which allows another full can to slide down upon the crushing members 22 and 23 to be in turn cut and emptied. The spring 55 51 causes the tripper 49 to catch the next can and hold it until the cam 59 reengages the finger 50. The counting mechanism 52 is positioned where it registers the cans in the last position before being operated upon.

60 By providing the box-part 19 of the cutter with the continuous cutting edge sloping evenly from the point 67 to the side opposite, I further provide an improved cutter that makes a smooth, clean cut edge and is 65 particularly efficient in conjunction with the

suction control of the contents provided during the act of emptying the cans by the box-part of the cutter. In the modified and preferred form of cutter, Fig. 13 the cutting points 92 and 93 function in conjunction 70 with the other portions of the cutting edge as a truing die, so that the edges of the ends of the can are caused to be straightened.

Obviously, changes may be made in the form, dimensions, and arrangements of the 75 parts of my invention without departing from the principles thereof, the above setting forth only a preferred form of embodiment.

I claim:

1. A machine for flattening rectangular cans embodying a three sided cutter disposed to move to and from a can to cut said can on three sides, two crushing members normally assuming a V-shaped position to hold 85 a rectangular can on edge while said cutter is operating, and means to cause said crushing members to close together whereby the can is flattened.

2. A machine for flattening rectangular 90 cans embodying a three sided cutter disposed to move to and from a can to cut said can on three sides, two crushing members normally assuming a V-shaped position to hold a rectangular can on edge while said 95 cutter is operating, means to cause said crushing members to close together whereby the can is partly flattened, and two flattening rollers disposed to receive the partially flattened can, draw said can up and complete 100 the flattening operation.

3. A machine for flattening rectangular cans embodying a box-cutter disposed to move to and from a can to cut said can on three sides, two crushing members normally 105 assuming a V-shaped position to hold a rectangular can on edge while said cutter is operating, and means to cause said crushing members to close together whereby the can is flattened.

4. A machine for flattening rectangular cans embodying a box-cutter disposed to move to and from a can to cut said can on three sides, two crushing members normally 115 assuming a V-shaped position to hold a rectangular can on edge while said cutter is operating, means to cause said crushing members to close together whereby the can is partly flattened, and two flattening rollers disposed to receive the partially flattened 120 can, draw said can up and complete the flattening operation.

5. A machine for flattening rectangular cans embodying a box-cutter disposed to move slowly toward a can to cut said can on three sides and to withdraw quickly to create a suction on the contents of the can whereby said contents are quickly removed, two crushing members normally assuming a V-shaped position to hold a rectangular can on 130

- edge while said cutter is operating, and means to cause said crushing members to close together whereby the can is flattened.
6. A machine for flattening rectangular cans embodying a box-cutter disposed to move slowly toward a can to cut said can on three sides and to withdraw quickly to create a suction on the contents of the can whereby said contents are quickly removed, two crushing members normally assuming a V-shaped position to hold a rectangular can on edge while said cutter is operating, means to cause said crushing members to close together whereby the can is partly flattened, and two flattening rollers disposed to receive the partially flattened can, draw said can up and complete the flattening operation.
7. A machine for flattening rectangular cans embodying a three sided cutter which cutter has two continuous cutting edges, said cutter being disposed to move to and from a can to cut said can on three sides, two crushing members normally assuming a V-shaped position to hold a rectangular can on edge while said cutter is operating, and means to cause said crushing members to close together whereby the can is flattened.
8. A machine for flattening rectangular cans embodying a three sided cutter which cutter has two continuous cutting edges, said cutter being disposed to move to and from a can to cut said can on three sides, two crushing members normally assuming a V-shaped position to hold a rectangular can on edge while said cutter is operating, means to cause said crushing members to close together whereby the can is partly flattened, and two flattening rollers disposed to receive the partially flattened can, draw said can up and complete the flattening operation.
9. A machine for flattening rectangular cans, two box cutters each of which cutters has two continuous cutting edges, said cutters being disposed to move slowly while cutting said can on three sides of each end and to withdraw quickly whereby is created a suction on the contents of the can and whereby said contents are quickly removed, two crushing members normally assuming a V-shaped position to hold a rectangular can on edge while said cutter is operating, and means to cause said crushing members to close together whereby the can is flattened.
10. A machine for flattening rectangular cans, two box cutters each of which cutters has two continuous cutting edges, said cutters being disposed to move slowly while cutting said can on three sides of each end and to withdraw quickly whereby is created a suction on the contents of the can and whereby said contents are quickly removed, two crushing members normally assuming a V-shaped position to hold a rectangular can on edge while said cutter is operating, means to cause said crushing members to close together whereby the can is partly flattened, and two flattening rollers disposed to receive the partially flattened can, draw said can up and complete the flattening operation.
11. A machine for flattening rectangular cans embodying two three sided cutters each of which cutters has two continuous cutting edges, said cutters being disposed to move to and from a can to cut each end of said can completely on three sides, a roller bearing against each of said can ends whereby said ends are forced inwardly, two crushing members normally assuming a V-shaped position to hold a rectangular can on edge while said cutter is operating, and means to cause said crushing members to close together whereby the can is flattened.
12. A machine for flattening rectangular cans embodying two three sided cutters each of which cutters has two continuous cutting edges, said cutters being disposed to move to and from a can to cut each end of said can completely on three sides, a roller bearing against each of said can ends whereby said ends are forced inwardly, two crushing members normally assuming a V-shaped position to hold a rectangular can on edge while said cutter is operating, means to cause said crushing members to close together whereby the can is flattened.
13. A machine for flattening rectangular cans embodying two three sided cutters each of which cutters has two continuous cutting edges, said cutters being disposed to move to and from a can to cut each end of said can completely on three sides, said cutter having two truing cutter points on the fourth side, a roller bearing against each of said can ends whereby said ends are forced inwardly, two crushing members normally assuming a V-shaped position to hold a rectangular can on edge while said cutter is operating, and means to cause said crushing members to close together whereby the can is flattened.
14. A machine for flattening rectangular cans embodying two three sided cutters each of which cutters has two continuous cutting edges, said cutters being disposed to move to and from a can to cut each end of said can completely on three sides, said cutter having two truing cutter points on the fourth side, a roller bearing against each of said can ends whereby said ends are forced inwardly, two crushing members normally assuming a V-shaped position to hold a rectangular can on edge while said cutter is operating, means to cause said crushing members to close together whereby the can is partly flattened, and two flattening rollers disposed to receive the partially flattened can, draw said can up and complete the flattening operation.

disposed to receive the partially flattened can, draw said can up and complete the flattening operation.

15. In combination with a can flattening machine, a box-cutter having a three sided cutting edge but said edge is formed sloping from a single point whereby is provided a cutter having in final effect two continuous cutting edges, and said cutter having two 15 truing cutter points on the fourth side.

machine, a box-cutter having a three sided cutting edge but said edge is formed sloping from a single point whereby is provided a cutter having in final effect two continuous cutting edges, and said cutter having two 15 truing cutter points on the fourth side.

In witness whereof, I hereunto subscribe my name this 30th day of October, A. D. 1919.

FRANK J. COURTNEY.

10 16. In combination with a can flattening
